DOOR OPERATING MECHANISM

Julius A. Schweig, St. Louis, Mo.

Application January 6, 1934, Serial No. 705,501

11 Claims. (Cl. 268—59)

This invention relates to door operating mechanisms, and more particularly to operating mechanisms for elevator doors of the vertically sliding, counterbalanced type.

5 The subject matter hereof is in part a continuation of my application Serial No. 491,889 filed October 29, 1930 for patent for Door operating mechanism, now No. 1,943,042.

One of the principal objects of the present invention is to provide a simple and efficient door operating mechanism of the above type which can be quickly and easily mounted on the elevator without material alteration thereof. Other objects are to provide for lubrication, economy 15 of construction, compactness of design and fewness of parts. The invention consists in the door operating mechanism and in the construction, combinations and arrangements of parts herein-after described and claimed.

20 In the accompanying drawings, which form part of this specification and wherein like symbols refer to like parts wherever they occur,

Fig. 1 is an interior side elevation of the door side of an elevator shaft, showing the doors on 25 adjacent floors each equipped with a door operating mechanism embodying my invention.

Fig. 2 is a vertical section through the door side of the shaft on the line 2—2 in Fig. 1,

Fig. 3 is an enlarged fragmentary interior side 30 view of the door on the side of the shaft in the region of the operating mechanism for one of the doors,

Fig. 4 is a horizontal section on the line 4—4 in Fig. 3,

Fig. 5 is a vertical section on the line 5—5 in Fig. 4,

Fig. 6 is a vertical section on the line 6—6 in Fig. 4,

Fig. 7 is a horizontal section on the line 7—7 in Fig. 3,

Fig. 8 is a vertical section on the line 8—8 in Fig. 3; and

Fig. 9 is a diagrammatic view showing a door operating mechanism of modified form.

45 Referring to Figs. 1 to 8, inclusive, of the accompanying drawings, the present preferred form of my invention is shown in connection with an ordinary freight elevator comprising a shaft A having a door opening B at each floor which is 50 closed by means of a vertically sliding, counterbalanced door comprising upper and lower door sections C and D, respectively. The upper and lower sliding door sections of each door are provided along each vertical edge with an angle bar 55 side frame member 4 slidably arranged in angle

bar door guides 2 that are rigidly secured to each other and to the wall of the elevator shaft A.

The upper and lower door sections of each door are hung on flexible cable chains 3 that pass over sheaves 4, 4a located within the shaft adjacent to the upper corners of the door opening B. One end of each door supporting chain 3 is suitably connected to the adjacent lower corner of the upper door section C; and the other end of said chain is connected to the upper end of an upright 10 rod 5, whose lower end is secured to the outer end of an arm 6 that projects horizontally from the adjacent upper corner of the lower door section D. By this arrangement, one door section acts as a counterbalance for the other, and the 15 two sections move simultaneously towards and away from each other. The elevator construction thus far described is well known and it is considered unnecessary to illustrate it in detail.

The door on each floor is opened and closed 20 by means of a separate door operating mechanism driven by an electric motor, preferably a reversible torque motor 7, which can be stalled under a full load for several minutes without injury. The customary limit switches (not shown) 25 are employed for automatically stopping the motor when the door sections reach the limit of their opening and closing movements; and the usual push button stations (not shown) are provided on the elevator car and on each floor for starting, stopping and reversing the motors.

The electric motor is provided at the armature end of its housing with a flange 8 that is removably secured by cap screws 9 flatwise to the vertical face of a plate 10 provided with an opening 35 through which the armature shaft 11 of the motor extends. The armature shaft 11 is provided at its end with a spur pinion 12 which drives a larger spur gear 13 formed integral with the door supporting sheave 4. This door supporting 40 sheave has an elongated hub portion 14, which is fixed to a supporting shaft 15 and has a small gear 16 keyed or otherwise rigidly fixed thereto for rotation with said sheave and the large gear 13 thereon. The small gear 16 on the sheave 4 45 drives a gear 17 of the same diameter fixed to one end of a shaft 18 which has a sprocket wheel 19 fixed to the other end thereof that drives an endless sprocket chain 20 located in a horizontal channel 21 provided therefor in the interior 50 surface of the front wall of the elevator shaft A just above lintel 22 of the door opening B. Said sprocket chain 20 extends longitudinally of the channel 21 to the opposite side of the door opening where it passes around a sprocket wheel 23 55

fixed to a shaft 24 on which the door sheave 4a is rigidly mounted.

The drive gearing for the sheave 4 is enclosed within a suitable lubricant containing housing 25 provided at its top and bottom with vertical flanges 26 that are rigidly secured flatwise to the adjacent angle bar door guide 2, which is cut away to accommodate the portion of the housing that extends thereacross. Said housing has a recess in its motor opposing face of a size and shape adapted to accommodate the gears 12, 13, 16 and 17. The gear receiving recess chamber of the housing 25 is closed by means of a plate 27 that is removably secured to said housing by means of screws 30. The armature shaft 11 and the peripheral gear carrying portion of the sheave 4 extend through openings 31 and 32, respectively, provided therefor in the closure plate 27. Both of said openings are flanged to prevent leakage of oil therethrough, the flange of the sheave receiving opening 32 being seated in an annular groove provided therefor in a felt ring 33 seated in the adjacent face of the sheave 4.

The sprocket wheel 19 is located outside of the gear housing 25 with one end of its supporting shaft 18 extending into said housing and journaled in suitable antifriction bearings 34 provided therefor in said housing and the other end of said shaft is journaled in suitable antifriction bearings 35 mounted in a bracket 36 that is removably secured by cap screws 37 to the adjacent vertical face of said housing. The supporting shaft 15 for the combination gear and sheave 4 has one end supported in a suitable antifriction bearing 38 provided therefor in the gear housing 25; and the other end of said shaft is supported in similar antifriction bearings 39 provided therefor in the motor supporting plate 10. The motor supporting plate 10 is spaced from the gear housing 25, far enough to accommodate the sheave 4, by means of lugs 40 that are formed integral with said plate and are removably secured to the housing by means of cap screws 41. The motor supporting plate 10 is also provided with an arcuate flange 42 which overhangs the sheave 4 and constitutes a shield therefor.

The shaft 24 for supporting the sheave 4a and the driven sprocket wheel 23 is journaled in an arm 43 whose upper end is pivotally supported, as at 44, on the adjacent door guide 2 for vertical swinging movement towards and away from the sheave 4a so as to vary the distance between the two sprocket wheels and thus place the sprocket chain 20 cooperating therewith under the desired tension. The sheave and sprocket supporting arm 43 is adjusted preferably by means of a pair of nuts 45 that are threaded on a stud 46 rigidly secured to the adjacent door guide 2. The stud fits within a notch provided therefor in the free lower end of the arm with the adjusting nuts 45 disposed one on each side of said end of said arm.

The operation of the door operating mechanism is as follows: When it is desired to operate the door on a particular floor, the motor at that floor is started and the drive of said motor is transmitted through the intermeshing gears 12 and 13 to the sheave 4, thence through the intermeshing gears 16 and 17 to the sprocket wheel 19 and thence through the sprocket chain 20 to the sprocket wheel 23 which rotates with the sheave 4a in a direction opposite to the direction in which the sheave 4 is rotated. The drive is then transmitted from the oppositely rotating door sheaves 4 and 4a to the door chains 3 supported thereon

by means of the friction between the surfaces in contact, thereby causing the two door sections to slide in the door guides 2. The door sections are slid apart when the motor is operated in one direction and are brought together when the motor is reversed. 5

Fig. 9 represents the modified form of the preferred invention which was specifically shown and claimed in said application Serial No. 491,889. In this form of the invention the door sheave 4 is 10 provided with a gear 47 which drives a gear 48 located thereabove whose supporting shaft 49 has a sprocket wheel 50 fixed thereto that drives an endless sprocket chain 20a. The sprocket chain 20a extends across the shaft and passes around a 15 sprocket wheel 51 fixed to the door sheave 4a on that side of said shaft.

The hereinbefore described door operating mechanism has numerous advantages. It provides a simple and compact drive gear unit which 20 occupies a minimum amount of space in the elevator shaft and which can be easily mounted on said shaft without material alteration thereof. The motor, gears and door sheave adjacent thereto are adapted to be attached to and removed 25 from the shaft as a unit, and all of the gears run in lubricant contained in an oil-tight and dust-proof housing. The construction also provides a simple mounting for the driven sprocket wheel which is readily adjustable to take up slack in 30 the sprocket chain.

Obviously, the hereinbefore described arrangement admits of considerable modification without departing from the invention. Therefore, I do not wish to be limited to the precise arrangements shown and described.

What I claim is:

1. In a door operating mechanism, a door comprising vertically slideable upper and lower door sections, a pair of sheaves, chains passing over 40 said sheaves and connecting said door sections, an electric motor geared to one of said sheaves for driving the same, a gear rotatable with said sheave, a second gear driven by said first gear, a sprocket wheel rotatable with said second gear, 45 a sprocket wheel rotatable with the other sheave, and an endless sprocket chain passing over said sprocket wheels.

2. In a door operating mechanism, a door comprising vertically slideable upper and lower door 50 sections, a pair of sheaves, chains passing over said sheaves and connecting said door sections, an electric motor geared to one of said sheaves for driving the same, a gear rotatable with said sheave, a second gear driven by said first gear, 55 a sprocket wheel rotatable with said second gear, a sprocket wheel rotatable with the other sheave, an endless sprocket chain passing over said sprocket wheels, and means for moving said second mentioned sprocket wheel towards and away 60 from said first mentioned sprocket wheel to vary the tension of said endless sprocket chain.

3. In a door operating mechanism, a door comprising vertically slideable upper and lower door sections, a pair of sheaves, chains passing over 65 said sheaves and connecting said door sections, an electric motor geared to one of said sheaves for driving the same, a gear rotatable with said sheave, a second gear driven by said first gear, 70 a sprocket wheel rotatable with said second gear, a sprocket wheel rotatable with the other sheave, an endless sprocket chain passing over said sprocket wheels, means for moving said second mentioned sprocket wheel towards and away 75 from said first mentioned sprocket wheel to vary

the tension of said endless sprocket chain, said means comprising a pivotally mounted arm for supporting said second mentioned sprocket wheel, a fixed stud cooperating with the free 5 end of said arm, and a pair of nuts threaded on said stud on opposite sides of the free end of said arm.

4. In a door operating mechanism, a door comprising vertically slidable upper and lower 10 door sections, a door operating sheave, an electric motor geared to said sheave for driving the same, a gear rotatable with said sheave, a second gear driven by said first gear, a sprocket wheel rotatable with said second gear, a housing 15 for supporting said motor and for supporting and enclosing the entire gearing, a second door operating sheave, chains passing over said door operating sheaves and connecting said door sections, a second sprocket wheel rotatable with 20 said second door operating sheave, and an endless sprocket chain passing around said sprocket wheels.

5. In a door operating mechanism, a door comprising vertically slidable upper and lower 25 door sections, a door operating sheave, an electric motor, a pinion on the armature shaft of said motor, a gear on said sheave intermeshing with said pinion, a second gear rotatable with said sheave, a third gear driven by said second 30 gear in a direction opposite to that of said sheave, a sprocket wheel rotatable with said third gear, a second door operating sheave, chains passing over said door operating sheaves and connecting said door sections, a second sprocket wheel 35 rotatable with said second door operating sheave, and an endless sprocket chain passing around said sprocket wheels.

6. In a door operating mechanism, a door comprising vertically slidable upper and lower 40 door sections, a door operating sheave, an electric motor, a pinion on the armature shaft of said motor, a gear on said sheave intermeshing with said pinion, a second gear rotatable with said sheave, a third gear driven by said second 45 gear in a direction opposite to that of said sheave, a sprocket wheel rotatable with said third gear, a housing for supporting said motor and for supporting and enclosing said pinion and said gears, a second door operating sheave, chains passing over said door operating sheaves and connecting said door sections, a second sprocket wheel rotatable with said second door 50 operating sheave, and an endless sprocket chain passing around said sprocket wheels.

55 7. In a door operating mechanism, a door comprising vertically slidable upper and lower door sections, a door operating sheave, a sprocket wheel, an electric motor geared to said sheave and to said sprocket wheel for driving them in opposite directions, a second door operating sheave, chains passing over said door operating sheaves and connecting said door sections, a second sprocket wheel rotatable with said second 60 door operating sheave, and an endless sprocket chain passing around said sprocket wheels.

sprocket chain passing around said sprocket wheels.

8. In a door operating mechanism, a door comprising vertically slidable upper and lower door sections, a door operating sheave, a sprocket wheel, an electric motor geared to said sheave and to said sprocket wheel for driving them in opposite directions, a housing for supporting said motor, said sheave and said sprocket wheel and for supporting and enclosing the gearing for 10 driving said sheave and said sprocket wheel, a second door operating sheave, chains passing over said door operating sheaves and connecting said door sections, a second sprocket wheel rotatable with said second door operating sheave, and an 15 endless sprocket chain passing around said sprocket wheels.

9. In a door operating mechanism, a door comprising vertically slidable upper and lower door sections, a pair of sheaves, chains passing 20 over said sheaves and connecting said door sections, an electric motor geared to one of said sheaves for driving the same, a gear rotatable with said sheave, a second gear driven by said first gear, a sprocket wheel rotatable with said 25 second gear, a sprocket wheel rotatable with the other sheave, an endless sprocket chain passing over said sprocket wheels, a housing supporting and enclosing said gearing, and a plate removably secured to said housing and supporting said 30 motor.

10. In a door operating mechanism, a door comprising vertically slidable upper and lower door sections, a pair of sheaves, chains passing over said sheaves and connecting said door sections, an electric motor, a pinion on the armature shaft of said motor, a shaft for one of said sheaves, a gear on said sheave meshing with said pinion, a gear on said shaft, a second shaft, a gear on said second shaft meshing with the gear 40 on the first shaft, a sprocket wheel fixed to said second shaft, a sprocket wheel rotatable with the other sheave, an endless sprocket chain passing over said sprocket wheels, a housing enclosing said pinion and said gears, a plate secured to 45 said housing for supporting said motor, antifriction bearings in said housing for supporting one end of said shafts therein, an antifriction bearing in said plate for supporting the other end of said first shaft therein, a bracket secured 50 to said housing, and an antifriction bearing mounted in said bracket for supporting the other end of said second shaft therein.

11. In a door operating mechanism, a door comprising vertically slidable upper and lower 55 door sections, a pair of sheaves, chains passing over said sheaves and connecting said door sections, a gear rotatable with one of said sheaves, a second gear driven by said first gear, a sprocket wheel rotatable with said second gear, a sprocket 60 wheel rotatable with the other sheave, an endless sprocket chain passing over said sprocket wheels, and means operatively connected to one of said sheaves and sprocket wheels for driving the same.
